UNITED STATES PATENT OFFICE.

ALFRED T. PALMER, OF MEDFORD, MASSACHUSETTS.

CALLING DEVICE.

1,388,368.

Specification of Letters Patent.

Patented Aug. 23, 1921.

Application filed March 20, 1919. Serial No. 283,854.

To all whom it may concern:

Be it known that I, ALFRED T. PALMER, a citizen of the United States, residing at Medford, in the county of Middlesex and 5 Commonwealth of Massachusetts, have invented a new and useful Calling Device, of which the following is a specification.

This invention relates to calling devices wherein it is desired to send a pre-determined number of electrical impulses to a 10 distant point, as in automatic telephone systems, or the like, and has for its objects the housing of the calling mechanism within a hollow base such as may be employed in a 15 usual form of telephone desk-set; and the further simplification of the mechanism itself, said mechanism being preferably mounted, as a unit, upon the base-plate which serves as a floor to such desk-set. The 20 invention further consists in novel and practically noiseless means for setting up the calling impulses, and in the means employed for introducing a near-central pedestal within the path of motion of the manual 25 means which effect the impulses, without thereby materially reducing the number of impulses that may be sent.

It will be noted that the embodiment of 30 applicant's invention illustrated in the drawings is designed for use with a non-coördinating type of selector switch,—that is, a switch requiring but one setting of the calling lever; consequently, a variable stop is employed, *i. e.*,—one that may be set in 35 various positions to change the amplitude of motion permitted to said lever, in contradistinction from that style of calling lever used with a coördinating type of switch, wherein the stop is fixed in one position.

40 In the drawings that accompany and form part of this specification, I have illustrated my invention as applied to and made part of a telephone desk-set which is adapted to perform the other usual functions undisturbed; and the figures are described as follows:

Figure 1 is a general elevation of a telephone desk-set equipped with my invention, parts being broken away for clearness of 50 comprehension.

Fig. 2 is a partial plan section on line 2—2 of Fig. 1.

Fig. 3 is an enlarged general plan view, in section on line 3—3 of Fig. 1.

55 Fig. 4 is an under plan section on line 2—2 of Fig. 1.

Fig. 5 is an enlarged detail, in section on line 5—5 of Fig. 2.

Fig. 6 is an enlarged fragment of Fig. 1. The base B, pedestal P, transmitter T, 60 receiver R, receiver-hook H and receiver-switch S are shown in substantially the ordinary relative positions, excepting that the pedestal P is slightly removed from its usual central position on base B so as to permit 65 proper action of the calling-lever 1 and the stop-lever 2. This removal is slight in amount and leaves pedestal P in the paths of motion of levers 1 and 2; and it is quite 70 within the scope of my invention to employ 75 said pedestal to limit the extreme movements of said levers, if it is desired so to do.

Referring to the base B, Figs. 1, 3 and 4, I employ a base-plate 3, preferably covered with a felt layer 4, a top-plate 5, and a canopy 6, the last being preferably of pressed metal and having a near-central opening 75 that is provided, around the greater portion of its periphery, with a series of notches 7, each adapted to snugly house, in turn, the 80 arrow 8, said arrow being mounted on stop-lever 2 and adapted to hold said lever against rotation on its axis 9 while arrow 8 is in any of the notches 7. Stop-lever 2 is shown as a flat and somewhat elastic bar and is 85 provided with a handle 10. To change arrow 8 from one notch to another, a slight downward pressure on handle 10 is necessary to carry the bar and the arrow away from the under surface of the canopy adjacent to 90 the notched opening, after which handle 10, still held depressed, may be swung to any desired position and released. After setting stop-lever 2, with its arrow 8 in the desired 95 notch 7, the calling-lever 1 is operated by grasping its handle 11 and turning the lever until the down-turned lug 12 (Fig. 6) brings up against the bar of stop-lever 2, and then releasing handle 11, whereupon a coiled spring 13 operates to return calling-lever 1 100 to its initial position.

I show plates 3 and 5 as being joined through the agency of a series of posts 14 and screws 15, so that the calling mechanism may be mounted therebetween as a unit. 105 Canopy 6 may be secured by a series of screws 16 to corresponding ears 17 on base-plate 3, so it may readily be removed without displacing the calling mechanism.

Pedestal P is shown hollow and mounted 110 on a hollow, upwardly-projecting boss 18, which forms part of top-plate 5. A screw

19 (Fig. 1) may secure it in place and, at the same time, this screw may secure in place the plate 20 that carries hook-switch S.

Generally speaking, the calling mechanism 5 is designed to form a series of electrical contacts whose effects may be noted at some distant point as, for instance, a switch-board central to the telephone system. The essential features of this mechanism are the making and breaking of a circuit at some measured speed as, say, ten or twelve per second, and the pre-determination of the number of times the circuit is to be closed; it being understood that, when the mechanism is in 10 normal position, this circuit is open.

In the form illustrated, this mechanism comprises a star-wheel 21 (Fig. 4) and a pair of contact-springs 22 and 23 mounted as a switch in some usual manner, and insulated 15 from each other in said mounting. The spring 22 is backed with a blade 24, the latter being of insulating material, and they may be firmly united throughout their length or they may be in separate blades, as 20 desired. Spring 22 is preferably mounted radially with respect to star-wheel 21 and the tips of leaves 22 and 24 project slightly within the periphery of the teeth 25 of wheel 21. The other spring, 23, is sufficiently 25 elastic to engage the tips of teeth 25 with sufficient pressure to insure good electrical contact. The teeth 25 are formed on the metallic periphery of star wheel 21 and are preferably insulated from the shaft 26 by means of an insulating bushing 27. When star-wheel 21 is rotated in the direction of the arrow, the metal blade 22 will intermittently contact with the various teeth 30 25, each tooth serving to close the circuit and send one impulse to the switch-board. When wheel 21 is rotated in the opposite direction, the insulated blade 24 will contact the teeth 25 and no impulse is sent.

The connectors are, in general, omitted in 35 the drawings as they do not form part of this invention; but I have shown (Fig. 4) a simple diagram of a possible circuit to a distant point X, the wires Y and W being connected to the terminals of springs 22 and 50 23, respectively.

A source of energy is represented by the battery Z. This circuit, normally open at star-wheel 21, may be alternately closed and opened by the rotation of said wheel 21 in 55 the direction of the arrow, as above noted.

I prefer to make the mounting of springs 22 and 23 adjustable, in order to take up wear and, for this purpose, I mount the switch on a block 28, said block being held 60 by screws 29 through slots 30 in said block. A lug 31, threaded, may receive an adjusting screw 32, in a manner that is clearly shown in Fig. 4.

Star-wheel 21 is loosely mounted on shaft 65 26 but is rigidly connected to a pinion 33

(Fig. 5) which is in mesh with a large gear 34, the latter being fast on shaft 9. As lever 1 is also fast on shaft 9, rotation of lever 1 will cause a corresponding rotation of gear 34 and, through this gear, a rotation of pinion 33 and star-wheel 21. Thus it will be noted that when stop-lever 2 is moved from its normal position, seen in Fig. 3, to some pre-determined notch 7, see Fig. 1, lever 1 may be rotated, against the action of spring 70 13, until lug 12 brings up against lever 2, thereby rotating gear 34 and star-wheel 21 but causing no closure of the circuit W, Y. When lever 1 is released, spring 13 will automatically return it to normal position 80 (Fig. 3) and again rotate gear 34 and star-wheel 21, but in the opposite direction. This return rotation, in the direction of the arrow in Fig. 4, will cause a series of makes and breaks in circuit W, Y, agreeing in number 85 to the notch 7 employed. Star-wheel 21 is shown with eight teeth but I do not limit myself to any particular number for, as will be later noted, the speed of return of lever 1 may be regulated to insure the proper number 90 of impulses per second irrespective of the number of teeth 25. It is preferable, however, to so proportion the spacing of notches 7 that star-wheel 21 will give a corresponding number of impulses, but this is 95 a mechanical detail.

In practice, it is desirable that lever 1 may be set at any speed natural to the fingers of the operator; but it is preferable to regulate the speed of the return so as to insure 100 proper intervals between the impulses of star-wheel 21, in order that each impulse may have time to deliver its effect before the next overtakes it. For this reason, I introduce a drag upon the return of lever 1 in the 105 form of a governor 35 (Fig. 2), of any usual construction, said governor being fast with a pinion 36 on an auxiliary shaft 37.

In mesh with pinion 36 is a gear 38, loose on shaft 26, but so positioned as to be rotated by pinion 33 on the return only of lever 1. To insure the proper action of gear 38, I form a ratchet 39 fast upon pinion 33, and a series of spring-pressed pawls 40 pivotally mounted on gear 38 so that, when lever 1 is 115 being set, ratchet 39 slips by the pawls 40, but, upon the return of lever 1, ratchet 39 engages pawls 40 and thereby actuates governor 35 to regulate the return speed. I do not limit myself to the form of drag illustrated.

Referring to the unit construction of the calling mechanism, I have shown, in Fig. 4, several features which, while not essential to the spirit of this invention, are, nevertheless, capable of use in the forming of a practical calling device for telephone sub-station equipment. Thus, 41 represents what may be termed an "off-normal" switch adapted for operation by an insulated boss 130

42 mounted on a spoke 43 of gear 34. Also, 44 represents a switch usable in connection with a ringing button 45. Again, 46, 46 are two insulated segments adapted for the 5 mounting of a series of terminals 47, etc.

All of the above, as well as block 28, are preferably mounted on a spider 49, which may be secured to top-plate 5 by screws 50, 50.

10 I do not limit myself to the form of calling mechanism illustrated, except within the scope of the appended claims.

What I claim is:

1. A telephone base; calling mechanism 15 within said base; a shaft operatively connected with said mechanism and having one end projecting through said base; a lever fast on the projecting end of said shaft; a variable stop adapted to limit the movement 20 of said lever in one direction; and a telephone pedestal mounted on said base and so positioned as to limit the movement of said lever in the other direction.

2. A telephone base; calling mechanism 25 within said base; a shaft operatively connected with said mechanism; a lever fast on said shaft; a stop adapted to be set in a plurality of positions, all within the path of motion of said lever; and a telephone pedestal 30 mounted on said base and positioned within the path of motion of said lever.

3. A telephone base; calling mechanism 35 within said base; a shaft connected with said mechanism; a calling lever fast on said shaft; a stop lever loosely mounted on said shaft; means for setting said stop lever in various positions, all within the path of motion of said calling lever; and a telephone pedestal 40 mounted on said base and within the path of motion of said calling lever.

4. In a calling device, a hollow base for a telephone desk-set; impulse-sending mechanism mounted within said base; a rotatable lever positioned exteriorly with respect to 45 said base; a variable stop for limiting the rotation of said lever in one direction; automatic means for rotating said lever in the opposite direction; a pedestal mounted on said base and positioned to limit said rotation in the opposite direction; and means 50 whereby said automatic means shall cause the operation of said mechanism.

5. In a calling device, a wheel; a metallic-toothed periphery on said wheel; a contact-spring 55 radially mounted with respect to said wheel and having its free end positioned

within the periphery of said teeth; a second contact-spring insulated from the first contact-spring and so positioned as to be constantly in metallic connection with said 60 toothed periphery; and means for rotating said wheel.

6. In a calling device, a rotatable gear; a pinion in mesh with said gear; a toothed metallic wheel adapted for rotation by said 65 pinion; a contact-spring radially positioned with respect to said wheel and having its free end projecting within the outer periphery of said wheel; and manual means for rotating said gear.

7. In a calling device, a toothed, metallic wheel; a contact-spring radially mounted with respect to said wheel and having its free end projecting within the outer periphery of said wheel; insulating means mounted 75 on one side of said free end; and means for rotating said wheel in both directions.

8. In a calling device, a toothed, metallic wheel; a contact-spring radially and adjustably mounted with respect to said wheel; 80 insulating means mounted on one side of the free end of said spring; and means for rotating said wheel in both directions.

9. In a calling device, a rotatable wheel 85 with a metallic, toothed periphery; a metallic elastic blade positioned radially with respect to said wheel and having its free end positioned to contact with said teeth when said wheel is rotating in one direction; and means for rotating said wheel in both 90 directions.

10. In a calling device, a rotatable wheel with a metallic toothed periphery; a metallic elastic blade positioned radially with respect to said wheel and having its free end 95 positioned to contact with said teeth when said wheel is rotating in one direction; means for rotating said wheel in both directions; and means for automatically retarding said rotation in said one direction.

11. In a calling device, a shaft; a gear mounted on said shaft; manual means for rotating said gear in one direction; a movable stop for limiting said rotation; automatic means for rotating said gear in the 105 opposite direction; a fixed stop for limiting said latter rotation; a rotatable impulse-wheel; means for causing said gear to rotate said wheel in both directions; and automatic means for retarding said latter rotation.

ALFRED T. PALMER.
